J. J. McGUCKIN.
FLASH LIGHT.
APPLICATION FILED AUG. 25, 1916.

1,211,465.

Patented Jan. 9, 1917.

Inventor:

John J. McGuckin

By Andrew Wilson, Attorney.

UNITED STATES PATENT OFFICE.

JOHN J. McGUCKIN, OF BROOKLYN, NEW YORK.

FLASH-LIGHT.

1,211,465.

Specification of Letters Patent. Patented Jan. 9, 1917.

Application filed August 25, 1916. Serial No. 116,770.

To all whom it may concern:

Be it known that I, JOHN J. McGUCKIN, a citizen of the United States, residing at No. 633 Fifty-fourth street, borough of Brooklyn, county of Kings, city and State of New York, have invented certain new and useful Improvements in Flash-Lights, of which the following is a specification.

My invention relates particularly to hand 10 torches or flash lights such as are commonly arranged with storage batteries housed in cylindrical bodies or casings and adapted to supply current to an electric bulb located at one end of the casing. And my improvements 15 are particularly directed to means for preventing the rolling out of place of such flash lights when they are laid upon inclined surfaces.

In the drawings Figure 1 is a side view 20 of a flash light embodying my improvements; Fig. 2 is an end view on an enlarged scale looking to the right on Fig. 1; Fig. 3 is a view partly in section, and also on an enlarged scale, of the left hand end of 25 Fig. 1; Fig. 4 is a sectional detail of a modified form of the anti-rolling ring; Fig. 5 is a front view of a modified form of the anti-rolling device; Fig. 6 is a vertical, sectional view of the same, showing the retaining 30 lugs bent in; Fig. 7 is a front view of the same, showing the lugs in the same position as in Fig. 6; Figs. 8 and 11 are front views of modified forms of the anti-rolling device; Fig. 9 is a vertical, sectional view, and Fig. 35 10 is a partial front view of another modification of the anti-rolling device.

Similar reference numerals designate similar parts in all the figures.

1 is a conventional, cylindrical body of a 40 flash light, which is provided with the flared end 2 carrying the usual thread 3 and provided with the lens 4 held in place by the flanged screw collar 5.

6 is a supplementary collar-like element, 45 which is provided, upon a rounded circumference, with portions which project beyond the circumference of a true circle; and these projections may be either formed by the angles made by plain surfaces, as shown in 50 the polygonal forms illustrated in a number of the figures; or they may be in the nature of knobs or curved projections, as illustrated, for instance, in Figs. 8 and 11. Whichever form is adopted its function is to 55 prevent the rolling of the flash light to

which it is attached. And the attachment may be made in a permanent manner, as, for instance, by crimping a flange 7 of the anti-rolling attachment around the flange 8 of the conventional, threaded collar; or by 60 turning in lugs 9, 9, as in Figs. 5, 6 and 7, around the flange 8; or by forming the anti-rolling attachment with gripping elements such as the turned in prongs 10, 10 of Figs. 9 and 10, which will bear against and around the collar 5, if the element 6 is shoved over the collar, and will hold the element 6 detachably attached to the collar; or the screw threaded collar 5 may be made integral with the element 6 as illustrated in Fig. 4, in 70 which case a separate, conventional collar may be dispensed with.

The opposite end of the flash light may be provided with a smaller anti-rolling device, similar to that used upon the reflector 75 end; or a modified form, such as shown in Fig. 1, may be used, wherein a cap having a polygonal flange 11 carries a screw threaded sleeve 12 which takes the place of the ordinary cap upon that end of the flash 80 light body.

By means of my improvements I am enabled to simply, cheaply and effectively provide the ordinary flash light holder with an anti-rolling attachment which is both attractive in appearance, easy of application, and effective in operation, and which will materially increase the convenience of the flash light holder in use, because the user, when employing the flash light holder, may 90 lay it down upon sloping surfaces of ordinary pitch without fear of its rolling out of position to its possible injury and to his inconvenience.

Having thus described my invention, what 95 I claim and desire to secure by Letters Patent of the United States is:—

1. The combination, with a cylindrical flash-light holder, of a unitary, lens-retaining and anti-rolling device having an 100 external contour other than cylindrical.

2. The combination, with a cylindrical flash-light holder, of a detachable, unitary, lens-retaining and anti-rolling device having an external contour other than cylindrical. 105

3. The combination, with a cylindrical flash-light holder, of a detachable, unitary, lens-retaining device having a plurality of anti-rolling elements protruding therefrom, 110

and a detachable, end-closing cap having a plurality of anti-rolling elements protruding therefrom.

4. The combination, with a cylindrical flash-light holder, of a unitary, lens-securing device having a plurality of anti-rolling elements protruding therefrom.

5. The combination, with a cylindrical flash-light holder, of an anti-rolling device provided with flexible, metallic elements for attaching it to the flash-light holder.

6. The combination, with a cylindrical flash-light holder, of a lens-holding collar and a sheet metal, anti-rolling device having a noncylindrical external contour and being 15 provided with flexible elements whereby it is secured in a unitary relation with the lens-holding collar.

JOHN J. McGUCKIN.
